UNITED STATES PATENT OFFICE

OTTO MAR PODLEJSI, OF VIENNA, AUSTRIA, ASSIGNOR TO THE FIRM GESELLSCHAFT FUER PATENTVERWALTUNG A. G., OF SCHAFFHAUSEN, SWITZERLAND

TYPE-WHEEL TYPEWRITER

Application filed November 1, 1927, Serial No. 230,238, and in Austria November 9, 1926.

This invention relates to a type-wheel typewriter and its object is to render possible the operation of the same in such a manner, that all movements correspond with the natural position and movement of the fingers of the operator. The typewriter according to the present invention is of simple construction and small size, and is readily portable.

The object is attained according to the present invention in that the operating lever for moving the type-wheel into the position of typing is horizontally movable about a vertically disposed shaft and carries the type-wheel and its operating gear as well as the ink-roller. The feed of the slide carrying the paper-roller and also the inking of the types by means of the ink-roller is effected by the movement of this single operating lever, which carries the type-wheel and also serves for guiding the rack setting the type-wheel.

The invention is illustrated in the accompanying drawings in which Fig. 1 is a plan view, partly in section, with the cover removed; Fig. 2 a transverse section on the line 2—2 of Fig. 1; Fig. 3 a transverse section on the line 3—3 of Fig. 1; Fig. 4 a plan view with the cover in position and Fig. 5 an elevational view with the cover and certain springs omitted.

The main-lever 3 is movably mounted on a pin 2 of the bed-plate 1 and provided with a lateral extension 4 for operation by the thumb of the operator. The lever 3 may be rotated about the vertical pin 2 until the lever strikes a stop hereinafter described. As a result of rotating the lever 3 a type-wheel 5, which is rotatable about a pin 6 of the main-lever 3, cooperates with a paper-roller 7, the latter being rotatably mounted in bearings 8 of the paper carriage 8', the toothed bar 9 of which is slidably mounted in guides of the bed-plate 1. At the rear, the paper carriage 8' is supported on the upturned edge of the bed-plate 1 and is pressed against the same by a spring 8''. A double armed lever 11 is rotatable about a pivot 10 of the main-lever 3 and moved towards the toothed bar 9 of the roller-slide by means of a spring 12, which is attached to the lever 11 near its pivot 10. During the rotation of the

main-lever 3, the free end of the lever 11 engages the teeth of the bar 9 of the paper carriage feeds and forward the latter for one tooth, because the main-lever 3 rotates about the pivot 2 until the end of the arm of the lever 11 engages a stop 14 fixed to the bed-plate. Now the feeding operation of the roller-slide is at an end the lever 11 is provided with an elongated slot 15, through which passes the pivot 10, in order to render possible a further rotation of the main-lever for pressing the type-wheel 5 onto the roller 7 without feeding the paper carriage. By means of a spring 16, one end of which is secured to the pivot 10 while the other end thereof is attached to the lever 11, the latter is pulled towards the type-wheel 5 but can yield in its bearing during its cooperation with the stop 14. By pressing on the end 11' of the lever 11 the latter may be disengaged from the bar 9 and the carriage may then be moved by hand. Instead of mounting yieldingly the lever 11, the same may be mounted unyieldingly. However in this case the lever 11 would have to be shaped in such a manner, that its arm, resting on the fixed stop 14 can yield for instance by reducing the length of the lever-arm by bending. Further the main-lever 3 is retained by a spring 17 in a position in which the type-wheel 5 is removed from the paper-roller.

The type-wheel is set by a rack 18, which is guided in the bracket 13 and in the extension 29 on the main-lever 3 and on its end, extending beyond the side of the typewriter, carries an arm 20, which is rotatable about a pivot 19 and the free end of which plays above figure-plate 21, the latter being secured to the cover 1'. Preferably a ball-shaped member 22 is secured to the free end of the arm 20 and is adapted to engage semi-spheric depressions 23 of the figure-plate 21 in case of a corresponding adjustment, because the arm 20 yields towards the plate 21. On adjusting the arm 20, the rack 18 is shifted and engages a gear 24 of the type-wheel 5 and adjusts the same.

The types are inked by an ink-roller 25, which is mounted on an arm 26, rotatable about a pivot 27, which is fixed to the bed-plate 1.

plate 1. The arm 26 passes round the type-wheel 5 and is provided with an extension 28, which extends beyond the pivot 27 and is engaged by the hook-shaped extension 29 of the main-lever 3. In case the latter is rotated, the arm 26 is rotated simultaneously in the direction of the arrow shown in Fig. 1, whereby the ink-roller 25 passes over the periphery of the type-wheel 5. The ink-roller 25 is mounted on a yielding extension 30 of the arm 26, so that it cooperates and rolls upon the periphery of the type-wheel. On the main-lever 3 is also mounted an ink storing roller 31, the path of the ink-roller 25 being such and the ink storing roller 31 being arranged in such a manner, that the ink-roller 25 also cooperates with the ink storing roller 31 and thereby is inked.

In the illustrated embodiment the types are arranged on the type-carrier of the type-wheel in three superposed horizontal zones 32. The type-wheel 5 is arranged vertically slidable on its pivot 6 and forms a unit with the toothed wheel 24 and near its pivot its under face is engaged by a lever 33, which is fulcrumed to the bed-plate 1. A depression key 34 is pivotally attached to an arm 36 of the lever 33 by means of a pin 35, so that on depressing the key 34, the lever 33 is moved and lifts the type-wheel 5. The key 34 is rotatable about the pin 35 and retained in the upright position by means of a spring 37, in order to place into the typing position one of the type-zones 32 of the type-wheel 5 according to requirement and thus lift the latter to a greater or smaller extent. On the bed-plate 1, adjacent to the key 34, is arranged a stop 38 and the said key can move past the latter in the adjusted position controlled by the spring 37, so that the key 34 can be wholly depressed and the type-wheel can be wholly raised for setting the lower type-zones. In case it is desired to set the higher type-zone only, the key 34 is rotated about the pivot 35 in the direction of the arrow shown in Fig. 2, so that during its depression it cooperates with the stop 38 and consequently the type-wheel is raised to a smaller extent. In the position of rest, which is secured by a spring 38', the topmost type-zone is disposed in the position of typing.

A stop 39, arranged on the bed-plate 1, is guided on a pin 40 fixed to the bed-plate and is maintained in its uppermost position by a spring 41, in order to limit the rotation of the main-lever 3 towards the paper carriage. In the raised position a sufficient clearance remains between the stop 39 and the bed-plate 1, so that the main-lever 3 can swing up to the pin 40 and, by means of its lateral extension 42, contacts with the pin 40, thereby limiting its movement. The teeth 24 of the type-wheel 5, rotated by the main-lever 3, cooperate with a tooth 43 which is secured to

the plate 9" carried by the guide 9', thereby securing the setting of the type-wheel 5 in the position corresponding to the character to be typed. At the same time the teeth 24 of the type-wheel 5 adjust and secure the type to be depressed. In case it is desired to feed the slide without typing, the stop 39 is depressed against the action of the spring 41, so that it rests on the bed-plate 1. Now the lateral extension 42 of the main-lever 3 when the latter is oscillated strikes the stop 39, thus limiting the movement of the said lever without pressing the type-wheel 5 onto the paper-roller 7. A cover 45 of celluloid or a similar transparent material is rotatable about a pin 44 of the bearing 8 at the right hand side of the paper-roller 7, the said cover covering the right hand end of the latter as shown in Fig. 2. The cover 45 may be colored in a particularly striking color, in order to indicate to the operator, that the feeding operation is at an end. The cover 45 is of such a size, that thereby the normal length of a line is limited. If more characters are to be written, the cover 45 is rotated upward by depressing the extension 46, projecting beyond the pivot 44, whereby the paper roller is released.

I claim—

1. In a typewriting machine, the combination of a paper carriage, a lever oscillatable in a horizontal plane toward and from said carriage, a type wheel mounted on said lever and adapted to be moved thereby toward and from the carriage, means carried by said lever for feeding said carriage, an ink storing roller carried by said lever, a second lever pivoted in proximity to the type wheel, an inking roller carried by said second lever and means for oscillating the latter upon oscillation of the first mentioned lever to bring the inking roller successively into contact with the type wheel and the ink storing roller.

2. In a typewriting machine, the combination of a paper carriage, a lever oscillatable in a horizontal plane toward and from said carriage, a type wheel mounted on said lever and adapted to be moved thereby toward and from said carriage, a pivot carried by said lever, a double armed lever having an elongated slot through which said pivot extends, spring means engaging said pivot and a point of said double armed lever for yieldingly moving said double armed lever on said pivot and means for yieldingly causing one arm of said double armed lever to engage said carriage and feed the same on actuation of the first named lever.

3. In a typewriting machine, the combination of a paper carriage, a lever oscillatable in a horizontal plane toward and from said carriage, a type wheel mounted on said lever and adapted to be moved thereby toward and from the carriage, means carried by said lever for feeding said carriage, and an upwardly

spring pressed depressible stop for said lever adapted to permit said lever to swing the typewheel into contact with the carriage when in its upper position and to prevent said lever from swinging the typewheel into contact with the carriage when in its depressed position.

4. In a typewriting machine, the combination of a paper carriage, a lever oscillatable in a horizontal plane toward and from said carriage, a type wheel mounted on said lever and adapted to be moved thereby toward and from the carriage, means carried by said lever for feeding said carriage, an ink storing roller carried by said lever, a second lever pivoted on a fixed pivot, an inking roller carried at the end of said second lever, and cooperable extensions carried by said levers respectively and adapted to cause said second lever to oscillate about its pivot upon oscillation of the first named lever and move the inking roller successively into engagement with the type wheel and the ink storing roller.

5. In a typewriting machine, the combination of a paper carriage, a lever oscillatable in a horizontal plane toward and from said carriage, a type wheel mounted on said lever and adapted to be moved thereby toward and from the carriage, means carried by said lever for feeding said carriage, a gear on said type wheel, a rack bar adapted to mesh with said gear and rotate said type wheel, a table containing a reproduction of the characters on said type wheel and means movable over said table and cooperable with said rack bar to determine the extent and direction of movement thereof.

6. In a typewriting machine, in combination, a paper carriage, a lever oscillatable in a horizontal plane toward and from said carriage, a type wheel mounted on said lever and adapted to be moved thereby toward and away from the carriage, and an inking roller mounted adjacent said typewheel and adapted to be oscillated by said lever over the face of said typewheel before the latter comes into contact with said carriage.

In testimony whereof I affix my signature.

OTTOMAR PODLEJŠI.
